UNITED STATES PATENT OFFICE.

HERBERT D. WELLER, OF SAN JOSE, CALIFORNIA, ASSIGNOR OF THREE-FOURTHS TO WM. G. HAWLEY AND H. P. LARONETTE, OF SAN JOSE, CALIFORNIA.

MAIL-POUCH ADDRESS AND FASTENING ATTACHMENT.

SPECIFICATION forming part of Letters Patent No. 699,431, dated May 6, 1902.

Application filed June 10, 1901. Serial No. 63,974. (No model.)

To all whom it may concern:

Be it known that I, HERBERT D. WELLER, a citizen of the United States, residing at San Jose, county of Santa Clara, State of California, have invented an Improvement in Mail-Pouch Address and Fastening Attachments; and I hereby declare the following to be a full, clear, and exact description of the same.

My invention relates to improvements in mail and like pouches.

My invention comprises details of construction which will be more fully explained by reference to the accompanying drawings, in which—

15 Figure 1 is a front view of the upper part of the pouch. Fig. 2 is a rear view of the same. Fig. 3 is a longitudinal section through the locking end of the strap. Figs. 4 and 5 are transverse sections through the same. 20 Fig. 6 is a bottom view of the same. Fig. 7 shows the flap partially thrown open.

In the ordinary construction and use of mail-pouches a flap is made to turn over the open end of the pouch and staples are provided through which a strap is passed with a latching device which fits over a staple, and the whole is secured by an independent and removable padlock. Such locks are liable to become misplaced or lost; and it is the object of my invention to permanently attach the lock to the bag and to form an end upon the strap which will engage with the lock and be secured thereby and in conjunction with this end an open slot through which the address-card may be introduced or removed, the end of said slot abutting against the lock, so that the single fastening secures the bag and the address-card in place.

As here shown, A is the bag, having a flap B, adapted to fold over the open end of the bag. This flap has staples 2 fixed to it at intervals, and these staples pass through protected slots, as at 3, which are made through both sides of the bag just below the mouth. 45 These staples having been passed through the slots project from the opposite side.

4 is a strap one end 5 of which is loosely and permanently attached to a staple, as at 6. This strap is then passed through the staples 2, where they project through the rear

of the bag. Thence passing around the end of the bag the strap is passed through other staples 7, which are fixed upon the outside of the front portion of the flap.

8 is a lock of any suitable description, and 55 this lock is firmly secured to the front of the flap, with the opening to receive the latch or bolt essentially in line with the staples 7. This lock is preferably a spring-lock which will engage and hold the bolt when it is introduced, and the bolt is released by means of a key, which disengages the spring-catches of the lock. Upon the end of the strap is secured a channeled plate 9, and upon the end of this plate is the latch or bolt 10. This 60 latch or bolt is properly constructed to be engaged by the spring-catches of the lock when it is introduced, and when the strap has been passed through the staples 7 this bolt, being pushed into the lock, will at once be engaged 70 and secured. The channel in the part 9 may be formed by folding the metal from the front over the back or any other way, so as to form a sufficient space for the introduction of the address card or tag 11, which is pushed in 75 from the open end of the channel, just beneath the bolt 10. The front of the plate 9 has an opening made through it, communicating with the channel beneath and of such length and width as to expose the name or 80 address card, which has been placed in the channel. The introduction of the bolt 10 into the lock causes the end of the channel which contains the card to abut against the face of the lock, and thus close the channel and prevent any removal of the card. The parts are 85 released by the use of a key, which is introduced and turned in the lock, so as to disengage the bolt from the holding-catches, and the strap can then be withdrawn and the 90 pouch opened. The end of the channel containing the card is then exposed, so that the card can be removed or changed at pleasure.

Having thus described my invention, what I claim as new, and desire to secure by Letters 95 Patent, is—

The combination with a mail-pouch and a lock permanently secured to the flap thereof, and having an end opening, of a strap having one end secured to the flap, a channeled 100

plate secured to the free end of the strap said plate having a bolt projecting from its front end, the under side of said bolt forming the top wall of the channel at the entrance there-
5 to whereby the address card or label is inserted from beneath the bolt and its end is protected by the overhanging bolt, said bolt adapted to engage the end opening of the lock and the end of the card or label being in

line with the solid wall of the lock below the 10 opening.

In witness whereof I have hereunto set my hand.

HERBERT D. WELLER.
